BY *Charles J. Worth*

AGENT

LATCH RELAY MOTOR STRUCTURE

This invention relates generally to a magnetic latch relay of the type shown, described and claimed in my U.S. Pat. No. 3,470,510 which issued Sept. 30, 1969 and is assigned to the same assignee as is the present application. More particularly, the present invention is concerned with reducing reluctance resulting from the relationship of the parts providing flux paths.

As disclosed in my aforesaid patent, the core of the electromagnet could be made fully or in part of a material with remanent characteristics. When the core is polarized, the flux path through the remanent magnet material extends axially relative to the core. Where the core, especially when made fully of a remanent magnet material, extends through a bracket member of the frame also providing part of a flux path, the flow of flux from the bracket member must at that intersection cross at least some of the flux lines or lines of magnetic force of the core which then appears as reluctance. This, of course, reduces the motoring and latching effect of the available flux on the armature.

In my earlier configuration, the pole face area is dictated by the diameter of the core and determines the working airgap of a given design which is an operating limitation. It also has been found that magnetic flux or flux lines fed into softer magnetic materials will distribute more uniformly than flux entering harder magnetic materials with greater remanent characteristics which have been exposed to a magnetizing field of a different orientation.

Accordingly, an object of the present invention is to provide a magnetic latch relay in a manner which facilitates construction and reduces cost.

Another object of the present invention is to provide the foregoing relay having improved flux paths.

And another object of the present invention is to provide the foregoing relay having an optimum pole face area without sacrificing core diameter and coil winding relationships.

The foregoing and other objects and advantages will appear more fully hereinafter from a consideration of the detailed description which follows, taken together with the accompanying drawings wherein several embodiments of the invention are illustrated by way of example. It is to be expressly understood, however, that the drawings are for illustration purposes only and are not to be construed as defining the limits of the invention.

FIG. 1 is a side elevational view of a relay made in accordance with the present invention.

FIG. 2 is a fragmentary sectional view taken on line 2-2 of FIG. 1 with the armature removed.

FIG. 3 is a side elevational view of a modified relay construction, in accordance with the present invention, with the header removed.

FIG. 4 is a sectional view taken on line 4-4 of FIG. 3 with the header removed.

FIGS. 5, 6 and 7 are views similar to FIG. 3 each illustrating a different modified construction.

Referring now to the drawings and particularly to FIGS. 1 and 2, a relay made in accordance with the present invention is provided with a generally C-shaped support means or frame 10 having a base member 11, a bracket member 14 and a permanent magnet 16 to provide magnet means therebetween. The members 11 and 14, which are of soft magnetic material, are spaced from and substantially parallel to each other. Base member 11 has at one end an armature-supporting leg 12 which extends upwardly past member 14, and at its other end connecting means which, in this instance, is an upwardly extending leg or flange 13. Bracket member 14 has at one end a leg 15 which depends toward the base member 11.

Legs 12 and 15 are spaced from and substantially parallel to each other. The permanent magnet 16 is disposed in the space between and connected to the legs 12 and 15, thereby connecting the base and bracket members 11 and 14 together. Therefore, frame 10 includes a permanent magnet material.

To complete the general frame structure, an armature retainer member 17 is connected to the side of leg 12 opposite from the magnet 16. The lower end of retainer 17 is provided with a projection 18, which extends therefrom in a direction away from magnet 16, for retaining one end of a tail spring 19 as shown.

The novel relay is provided with an actuating means or electromagnetic 20 having a coil 21 and a core 22 which is suitably connected, preferably by welding, at its ends between the base member 11 and the bracket member 14. The bracket member 14 is provided with an offset portion 24 of predetermined or desired size at the end of the core 22, the upper surface of which forms a pole face 23 which is of substantially greater area than the end or cross-sectional area of the core. The core 22 is of a relatively hard remanent magnet material while the bracket 14 providing the pole face 23 is of soft magnetic material.

The permanent magnet 16 together with legs 12 and 15 are disposed on one side of the electromagnet 20, while a terminal header or block 25 is provided on the other side thereof and is connected to the flange 13 in any suitable manner well known in the art. The header 25 supports at least one fixed contact 26 or 27 which are spaced from each other and have terminal connection portions. The coil 21 is considered to be of simple construction wherein a single extent of wire is used for the coil windings and a pair of terminals 28 and 29, which are fixedly supported by the header 25, are provided for the wound wire. Coil 21 may be of complex construction having two separate sets of windings. If coil 21 is of complex construction, a second pair of terminals 28 and 29 would be required.

The armature, its pivotal support and the tail spring arrangement, as shown in FIG. 1 and which will be described briefly herein, is for illustration purposes only and is not intended to define the limits of the present invention. A relay construction corresponding to this illustrative combination of parts is shown, described and claimed in U.S. Pat. No. 3,201,541 granted Aug. 17, 1965, to me and assigned to the same assignee as is the present application. It should be further understood that recitation of the armature of magnetic material is to be construed in its broadest sense to include a nonmagnetic armature with a plate or layer of soft magnetic material as is required in the exemplary relay illustrated and described herein.

An armature 30 of soft magnetic material is pivotally supported at one end on the free end of leg 12 opposite from the base member 11. Armature 30 extends from its supported end toward header 25 and terminates in a free end which overlies the exposed surface or pole face 23. A pair of tails or tail portions 31 (only one shown) and a projection 32 spaced between the tails extend from the supported end of the armature 30 in a direction away from core 22. The tails 31 are then bent or angled relative to the major plane of the armature 30 and terminate in free ends which may abut leg 12 and limit the maximum pivotal displacement of the armature 30 from the core face 23 which is in a counterclockwise direction as viewed in FIG. 1. Tail spring 19 which is retained at one end by projection 18 of the retainer 17, is retained at its other end by the armature projection 32 and thereby is maintained under tension for biasing the armature 30 to pivot away from the exposed pole face 23.

A movable contact 36-37 is provided to cooperate with either one of or a pair of fixed contacts 26 and 27 to accomplish the relay switch operation. The contacts are not specific to the present invention. Therefore, only one pair of fixed contacts 26 and 27 with an associated movable contact 36-37 will be considered to facilitate description. An insulated block means 33 is connected to the armature 30 for mounting the spring arm 34 of a movable contact. One end of arm 34 extends from the mounting means 33 and away from header 25 to provide a connection terminal 35. Arm 34 also extends axially toward header 25 terminating in a free end disposed between fixed contacts 26 and 27. A pair of contact faces 36 and 37 are connected to opposite sides of the free end of

spring contact arm 34 to provide the requisite movable contact, and are so arranged that contact face 36 engages contact 26 when the relay is open or reset and face 37 engages contact 27 when the relay is closed or set.

It should readily be understood that there are substantially three sources of flux, namely, the permanent magnet means 16, the electromagnet 20 and the remanence of the core 22. Orientation of each flux source if it were considered by itself in the absence of such other sources would be unimportant. However, for proper relay operation or response the interaction of the magnetic forces derived from all such sources must be considered which necessitates orientation of each of the magnetic sources relative to the others.

The operation and flux paths of the novel relay are substantially as shown and described in my aforesaid U.S. Pat. No. 3,470,510. Unlike the earlier construction, flux from the bracket member 14 to the pole face 23 and/or the core 22 does not cut across the lines of force of the core. By varying the size of the offset portion 24 of the bracket member 14, the pole face 23, which defines the extent of the working airgap, can be provided with an optimum area without sacrificing the core diameter and coil winding relationship of the electromagnet. The more uniform flux path of the magnetic material of the offset portion 24 than that of a remanent magnet reduces the critical location of a point-to-point contact between the armature member 30 and the pole face 23. To state this another way, the possible reluctance variations across the closed working airgap depending upon the location of a point-to-point contact is substantially eliminated.

In addition to the preferred construction shown in FIGS. 1 and 2, other modified forms of construction in accordance with the present invention are shown in the drawings and now will be described.

Referring specifically to FIGS. 3 and 4, a relay (shown in part) is provided with a modified frame 40 which includes the base member 11 and permanent magnet 16 of the frame 10. The frame 40 is provided with a bracket member 41, of soft magnetic material, with a leg 42 connected to the magnet 16 corresponding to the bracket member 14 and its leg 15, respectively. Bracket member 41 is provided with an opening 43 instead of the offset portion 24.

One end of the core 22 of the electromagnet 20 is again connected to the base member 11 while the other end extends into the opening 43, which is oversized, and terminates substantially flush with the outer surface of the bracket member 41. A disc-like plate or cap 44 of a soft magnetic material is welded or otherwise suitably connected to the end of the core 22 and the bracket member to provide a magnetic couple and the desired pole face 45.

Referring now to FIG. 5, a modified frame 50, similar to frame 40 of FIGS. 3 and 4, is provided with the base member 11 and an L-shaped bracket member 51 of soft magnetic material similar to the bracket member 41. The bracket member 51 has a leg 52 suitably connected to one side of the permanent magnet 16, and differs from the bracket 41 only because the opening 43 is eliminated. The core 22 of the electromagnet 20 is now welded or otherwise suitably connected between the base member 11 and the bracket member 51, and the plate or cap 44 is similarly connected to the bracket member in alignment with the core.

All of the construction forms heretofore discussed, one end surface of the core 22 is suitably connected to the base member 11 and the other end surface is similarly connected to the bracket member 14 or 41, or the plate 44. The area of the pole face 23 or 45 defines or determines the extent of the working airgap and the cooperating face provided by the armature 30 on the other side of the working airgap opposite from the pole face.

With the core 22 connected between the base member 11 and the bracket member 51 as shown in FIG. 5, in the absence of the plate 44 the armature can be used to define or determine the pole face portion of the bracket member 11. One way to accomplish this, as shown in FIG. 6, is to provide an ar-

mature 55 of soft magnetic material with an offset end portion 56 which, in essence, corresponds to the offset face portion 24 of FIG. 1. Alternatively, the plate or cap 44 can be suitably connected to the armature 30 as shown in FIG. 7.

Although several embodiments of the invention have been illustrated and described in detail, it is to be expressly understood that the invention is not limited thereto. Various changes may also be made in the design and arrangement of the parts without departing from the spirit and scope of the invention as the same will now be understood by those skilled in the art.

I claim:

1. In a clapper-type magnetic latch relay, the combination comprising
frame means including a base member and a bracket member, both of a soft magnetic material;
permanent magnet means connected between said base and bracket members;
electromagnet means including a core of remanent magnet material magnetically coupled at one end surface to said base member on one side of said permanent magnet means, and extending axially from said one end surface toward said bracket member;
means for magnetically coupling the other end surface of said core to said bracket member, and providing a pole face of soft magnetic material which is of a greater area than the cross-sectional area of said core;
a spring-biased clapper-type armature means pivotably supported at one end by said base member on the one side of said permanent magnet means, and having a free end overlying said pole face and defining an airgap therebetween; and
said armature means being at least in part of a soft magnetic material providing a face at the free end of said armature means and a flux path between said face and said base member.

2. In a clapper-type magnetic latch relay, the combination in accordance with claim 1 wherein
said bracket member has a portion thereof offset toward said armature means and the other end surface of said core is connected to said offset portion thereby providing said means for coupling and providing said pole face.

3. In a clapper-type magnetic latch relay, the combination in accordance with claim 1 wherein
the free end portion of said armature means is offset toward said electromagnet means and the other end surface of said core is connected to said bracket member thereby providing said means for coupling and providing said pole face.

4. In a clapper-type magnetic latch relay, the combination in accordance with claim 1 wherein
the other end surface of said core and a plate member of soft magnetic material are connected in axial alignment with each other to said bracket member thereby providing means for coupling and providing said pole face.

5. In a clapper-type magnetic latch relay, the combination in accordance with claim 4 and
the other end surface of said core and said plate member are connected to opposite sides of said bracket member.

6. In a clapper-type magnetic latch relay, the combination in accordance with claim 4 wherein
said plate member connects the other end surface of said core and said bracket member to each other.

7. In a clapper-type magnetic latch relay, the combination in accordance with claim 1 wherein
said bracket member has an opening there through axially aligned with and of a larger size than said core;
said core extends into said opening with the other end surface thereof substantially coplanar with the surface of said bracket member adjacent the airgap; and
a plate member of soft magnetic material is connected to said coplanar surfaces in axial alignment with said core.

8. In a clapper-type magnetic latch relay, the combination in accordance with claim 1 wherein,

the other end surface of said core is connected to said bracket member and a plate member of soft magnetic material is connected to said armature in substantial axial

alignment with said core thereby providing said means for coupling and providing said pole face.
